US00D956399S

(12) **United States Design Patent** (10) **Patent No.:** **US D956,399 S**
Roman et al. (45) **Date of Patent:** **** Jul. 5, 2022**

(54) **SHOE**

(71) Applicant: **adidas AG**, Herzogenaurach (DE)

(72) Inventors: **Arnaud Sanjuan Roman**, Brooklyn, NY (US); **Anthony Mazoyer**, Nuremberg (DE); **Maurice Taylor**, Nuremberg (DE); **Markus Klaus Scharnagl**, Nuremberg (DE)

(73) Assignee: **adidas AG**, Herzogenaurach (DE)

(**) Term: **15 Years**

(21) Appl. No.: **29/787,917**

(22) Filed: **Jun. 9, 2021**

Related U.S. Application Data

(63) Continuation of application No. 29/699,574, filed on Jul. 26, 2019, now Pat. No. Des. 923,310.

(57) **CLAIM**

The ornamental design for a shoe, as shown and described.

DESCRIPTION

FIG. 1 is a left side view of a shoe showing the claimed design;

FIG. 2 is a right side view thereof;

FIG. 3 is a front view thereof;

FIG. 4 is a rear view thereof;

FIG. 5 is a top view thereof; and,

FIG. 6 is a bottom view thereof.

The broken lines in the figures and the area(s) within the broken lines show portions of the shoe that form no part of the claimed design.

1 Claim, 6 Drawing Sheets
